MARKING MACHINE

Claude A. Putnam and Charles F. Robbins, Keene,
and Charles H. Cheeseman, Marlboro, N. H., as-
signors to Markem Machine Company, Keene,
N. H., a corporation of New Hampshire

Application December 11, 1937, Serial No. 179,364

12 Claims. (Cl. 101—38)

This invention relates to marking machines and it has for one of its objects to provide a novel marking machine adapted to make a printed impression on a convexedly curved surface such, for instance, as a cylindrical surface.

A further object of the invention is to provide a marking machine of this type with a novel inking mechanism which permits the successful use of a quick-drying ink so that the articles on which the printed impression is made can be handled or manipulated as soon as the printed impression has been made without danger that the said printed impression will be smeared or injured.

15 Further objects of the invention are to improve marking machines of this type in various particulars which will be more fully hereinafter set forth and then pointed out in the appended claims.

20 In the drawings wherein we have illustrated a selected embodiment of our invention;

Fig. 1 is a front view of a marking machine embodying the invention;

25 Fig. 2 is a partial sectional view with the section taken vertically through the shaft 5;

Fig. 3 is a section on substantially the line 3—3, Fig. 1;

Fig. 4 is a fragmentary sectional view showing part of the driving mechanism;

30 Fig. 5 is an enlarged sectional view of the steady rest for one end of the article being marked;

Fig. 6 is a top plan view of the inking reservoir;

35 Fig. 7 is a section on substantially the line 7—7, Fig. 6;

Fig. 8 is a sectional view through the ink reservoir on the line 8—8, Fig. 7;

40 Fig. 9 is a fragmentary sectional view showing the means for rotating the article holder;

Fig. 10 is a fragmentary section on the line 10—10, Fig. 2 showing the means for ejecting the marked article from the holder.

45 As stated above, this invention relates to a machine for making a printed impression on convexedly curved surfaces, and while the machine embodying the invention is adapted for making such printed impressions on a great variety of articles having convexedly curved surfaces we have herein illustrated it as it might be used in making a printed impression on the base of vacuum tubes such as are used in radios and the like. We wish it understood, however, that the invention is not limited to marking vacuum tubes 50 but can be used equally well for marking other cylindrical articles or articles having convexedly curved surfaces.

55 In the drawings the vacuum tubes which are to be marked are indicated at 1. The machine herein illustrated is designed to make a printed

impression on the cylindrical base portion 2 of the vacuum tube. This base portion 2 is usually of Bakelite or of similar insulating material and the machine herein shown is constructed so that a quick-drying ink can be used in making the 5 printed impression with the result that the marked articles can be handled almost as soon as the printed impression has been made without danger of smearing or injuring the printed 10 impression.

Our improved machine comprises a rotatable holder 3 in which the article 4 to be marked is held during the printing operation and the printed impression is made by means of a rotary printing pad constructed to have a rolling contact with the cylindrical surface of the article to be marked, the rotary holder for said article serving to give it the required rotative movement to provide for such rolling contact.

20 In the present embodiment of our invention we propose to employ a plurality of such article holders 3 which are mounted on a turret member 4, said article holders having a radial arrangement on said turret. This turret member 4 is shown as mounted on the horizontal shaft 25 505 which in turn is supported in suitable bearings carried by the frame 7 of the machine. Suitable means, which will be presently described, are provided for giving the turret 4 a step-by-step rotary movement thereby to bring the article carriers 3 successively into printing position, and while any article carrier is thus in printing position, the printed impression will be made on the article 4 carried thereby.

30 These article holders 3 may have various 35 shapes dependent upon the character of the article to be printed. In the present embodiment of the invention each article holder is provided at its outer end with a socket 5 adapted to receive the end of the base 2 of the vacuum tube 40 1, said socket being of such a size as to tightly fit the base with sufficient friction so that the article will be retained in the socket. Each article holder is mounted in the turret 4 to rotate about a radial axis, and, as best seen in Fig. 2, 45 these article holders are supported in suitable bearings 8.

40 The type member by which the printed impression is made on the article is shown at 9 and this is mounted on a head 10 which is secured to a vertical shaft 11 that is supported in suitable bearings 12 carried by the frame 7. The type-carrying surface of the type member 9 is formed on an arc struck from the axis of the shaft 11 as a center and during each rotation of the head 10 said type member 9 is 50 brought into register with the inking device, which will be presently described, and thereby receives a supply of ink, and during further rotation of the head said member 9 comes into 55 60

rolling contact with the base 2 of the vacuum tube, thereby leaving the printed impression on said base. Means are provided for positively rotating the article holder 3 while the printed impression is being made and at such a speed that the surface speed of the base 2 of the article will be the same as the surface speed of the type member 9.

The shaft 11 is driven from a driving shaft 13 by means of suitable spiral gears 14, said driving shafts 13 being shown as having a driving pulley 15 thereon from which it is driven.

The means for rotating the article carrier with the same surface speed as that of the type member 9 comprises a rack sector 16 carried by the rotating head 10, and the teeth of which are adapted to mesh with gear teeth 17 formed on the article carrier 3. The rack sector 16 is curved so that the tooth portion thereof is formed on the arc of a circle struck from the shaft 11 as a center, and said rack sector 16 thus functions as a gear sector which by the rotation of the head 10 is brought into engagement with the teeth 17 on the article carrier.

The gear sector 16 is slightly longer than the type member 9 so that during the rotation of the head 10 the teeth of the rack 16 will be brought into mesh with the teeth 17 of the article holder, as shown in Fig. 9, just before the type member 9 comes into contact with the article to be marked. The article will thus be rotating at the time that the type pad comes into engagement therewith, and as the type pad and the surface of the article to be marked have the same surface speed the rolling engagement between the type pad and the article will cause a clear printed impression to be made on said article.

As stated above the article holders 3 are mounted on an intermittently rotating turret 4 and means are provided for giving this turret an intermittent or step-by-step rotation in timed relation with the rotation of the head 10 so that at each rotation of said head the turret will be advanced angularly a distance equal to that between adjacent article holders 3. For thus intermittently rotating the turret we propose to use a device such as the well-known "Geneva" movement. The turret shaft 505 has the disk 18 fast thereon, which disk is provided with radial slots 19 and with the concavely curved surfaces 20 between the slots. The drive shaft 13 has fast thereon the other part of the "Geneva" movement in the form of the disk 21 having a pin 22 extending therefrom adapted to enter a slot 19 during each rotation of the shaft 13 and move said disk 18 forwardly one step. During the time that the pin 22 is out of engagement with the disk said disk is held from rotation by the circular flange 23 on said disk which is in engagement with one of the concavely curved surfaces 20.

In operating the device the attendant will insert a vacuum tube into each article holder 3 as it comes into the position of the article holder 3—*a* in Fig. 1, and at each rotation of the shaft 13 the turret 4 will be stepped forward a distance equal to that between two adjacent article holders. This forward movement of the turret takes place while the type pad 9 is out of engagement with the article and the turret is at rest while the head 10 is rotating through that part of its revolution in which the type pad 9 is in engagement with the article 1. At each rotation of the head 10, therefore, a fresh article will be brought into position to be marked and as soon as the

marking has been completed the turret is stepped forward to bring another article into printing position.

Means are provided for automatically ejecting the printed articles from their holders and for this purpose each article carrier is provided with an ejecting pin 24 which is situated axially thereof, and the inner end of which is adapted to engage an ejecting cam 25 carried by the frame 1 when the article holder reaches a position on the under side of the turret. The engagement of the inner end of each ejector pin with the cam 25 forces the pin outwardly in a radial direction, as shown in Fig. 10, and this outward movement forces the article 1 out from the recess 5 of the holder 3 as shown in Fig. 2. If desired, we may employ a receiving belt or carrier 26 to receive the articles as they are ejected from the article holders. Each ejector pin is provided with a collar 130 which is received in a recess in the turret, said collar serving to limit the extent of radial movement of the pin 24.

In order to hold each article steady while the printed impression is being made thereon we propose to employ a steady rest constructed to engage the upper end of the article while each printed impression is being made thereon. This steady rest comprises a plunger 27 which is mounted for vertical movement in a guiding member 28 carried by the frame 1. Said plunger 27 carries at its lower end a head 29 which is provided with an article-engaging member 30 adapted to engage the upper end of the article 1. This member 30 is mounted in the head 29 for free rotary movement about a vertical axis so that it is free to turn with the article 1 while the latter is rotating. The member 30 is shown as having a conical exterior shape and as being retained in the head 29 by means of the retaining ring 31, the latter having a conical lip 32 to embrace the larger end of the member 30. 33 indicates ball thrust bearings which facilitate the turning movement of the member 30.

Means are provided for raising the steady rest to withdraw it from engagement with the article 1 just before the turret makes each forward step, and then to lower the steady rest into engagement with the article after it has been brought into printing position. For this purpose there is provided the elbow lever 34 pivoted at 35 to the frame 1. The horizontal arm 36 of this elbow lever is slotted at its end, as shown at 37, and the slot engages a pin 38 carried by the plunger 27. Said horizontal arm of the lever 36 is engaged by a helical spring 39 which is confined between said arm 36 and an abutment 40 carried by the frame. For retaining this spring in position there is provided a pin 41 around which the pin is coiled and which extends through an aperture in the abutment 40. This abutment 40 is shown as adjustably carried on a post 42 rising from a portion 28 of the frame, and its position vertically of the post can be varied by means of nuts 43 which are screw-threaded to the post. The action of this spring 39 is to yieldingly force the steady rest in a downward direction and said spring yieldingly holds the steady rest against each article 1 while it is being marked.

Means are provided for raising the steady rest just before the turret is given each forward step, and for this purpose the head 10 has a post 44 rising therefrom in the axial line thereof, and said post 44 carries a cam 45 adapted to engage the lower end 46 of the vertical arm of the elbow lever 34. The engagement of the cam with the

elbow lever swings the latter clockwise, Fig. 2, thereby raising the steady rest, and the cam is so designed that this occurs just before the "Geneva" movement operates to give the turret 5 its forward movement, said cam serving to hold the steady rest raised until the turret comes to rest with another article in position to be marked. When the cam 45 passes out of engagement with the elbow lever 34 the steady rest moves downward 10 under the influence of the spring 39 and comes into engagement with the article which has just been brought into position to be printed.

The apparatus herein shown can be adjusted to make printed impressions on cylindrical articles of different diameter and can also be adjusted so as to place the printed impression at different locations in the direction of the axis of the cylindrical object.

To provide for making the printed impression 20 on articles of different sizes the type member 9 is mounted on the rotary table 10 so that said type member can be adjusted on said table in a radial direction, that is, it can be adjusted toward and from the axis of rotation of the article 1.

Said type member 9 is shown as carried by a slide 47 which is mounted on the head 10 in suitable ways 48 for movement in a radial direction. This slide 47 has a screw-threaded stem 49 projecting therefrom which extends through an ear 50 rising from and rigid with the head 10. 51 indicated adjusting nuts screw threaded to the stem 49 and which cooperate with the ear 50 for securing an adjusting movement of the stem in the direction of its length. These nuts 51 also act as lock nuts to hold the stem in its adjusted position. By this means the slide 47 can be moved to the right or to the left in Fig. 2 so as to adjust the type member 9 into the proper position to have the correct rolling engagement 40 with the article 1 regardless of the diameter of said article.

In order to make a proper printed impression the face of the type member 9 should be formed 45 on the arc of a circle struck from the center of the shaft 11 and having a radius equal to the distance between the axis of the shaft 11 and the surface on which the printed impression is to be made.

Since the curvature of an arc of a circle 50 varies with the radius thereof it follows that if the type member 9 is adjusted radially to any appreciable extent it would be necessary to provide for changing the curvature of the type member. The type member 9 is preferably made of 55 rubber or some slightly yielding material and it is secured to the curved face 52 of a removable type carrier 53. The type carrier 53 is in the form of a block having ribs 54 at its ends which are received in grooves 55 formed in two cheek pieces 60 56 that are secured to a head 57. This block 53 rests on a supporting plate 58 which is secured to the under side of the head 57. The block 53 with the type member 9 can be removed by simply raising the ribs 54 out of the grooves 55. This provides for readily replacing a block 56 which has 65 its curved face 52 formed on an arc of one curvature by another block 56 having its arcuate face 52 formed on a different curvature, and thus a block 52 and type member 9 can always be used 70 which has the correct curvature to provide an even rolling contact between the type member and the article to be marked regardless of the size of said article.

In order to provide the proper rolling contact 75 between the type 9 and the article to be marked

it is, of course, necessary that the pitch circle of the gear sector 16 should have the same radius as the circle in which the type 9 travels, and that the pitch circle of the pinion 17 should have the same diameter as that of the cylindrical article 5 at the point where the printed impression is to be made. To provide for this we have made the gear sector 16 removable from the head 10 so that when larger or smaller articles are to be marked and the type member is adjusted radially 10 correspondingly, the gear sector 16 may be removed from the head 10 and replaced by another gear sector having the correct pitch circle. The head 10 is shown as formed with a flat seat portion 59 against which the base 60 of the gear sector 15 rests and said gear sector is removably secured to the head 9 by suitable bolts 61. This enables any gear sector to be readily removed from the head and replaced by another one having the proper pitch circle. It will be understood that 20 in order to rotate the cylindrical surface 2 of the article 1 at the same surface speed as that of the type members 9 it is necessary not only that the gear sector 16 should have a pitch circle of the same diameter as the circular path of 25 movement of the type 9 but also that the pinion 17 should have a pitch circle of the same diameter as the cylindrical portion 2 on which the printed impression is to be made. We have, therefore, provided an article holder having such a construction 30 that the pinion 17 can be removed and replaced by another pinion and hence it is possible to always use a pinion having the correct pitch circle for the cylindrical article which is to be marked. In the construction herein shown the article holder 3 comprises the sleeve portion 62 and a spindle member 63 on which the sleeve portion is removably mounted. This sleeve portion 63 has at its outer end the article-receiving recess 5 and at its inner end it is formed with the pinion 17, and because it can be removed from the spindle member 63 it is possible to always use a sleeve 62 having a pinion portion 17 provided 35 with the correct pitch circle to correspond to the size of the article which is to be retained in the 40 recess 5.

We have referred above to the fact that the type member 9 can be adjusted vertically or in the direction of the axis of the article to be marked. This is provided for by making the 45 head 57 vertically adjustable on the slide 47. Said head is provided at its sides with ribs 64 which operate in ways formed by gibs 65 which are secured to the slide 47, and the vertical adjustment of the head 57 is secured by means similar to that employed for radially adjusting the slide 47. The head 57 has rigid therewith a laterally projecting ear 66 through which extends a screw-threaded stem 67 that is rigid with the slide 47 and rises therefrom. Two adjusting nuts 68, one on each side of the ear 66, are screw-threaded to the stem 67 and by manipulating these nuts the head 57 may be raised or lowered and locked in any adjusted position.

In practice we propose to use gear segments 65 16 and pinions 17 having gear teeth of a standard size, which means that the gear teeth are spaced a standard distance apart. Where pinions of different sizes all have gear teeth of the same size it follows that for those pinions in 70 which the length of the pitch circle is not an exact multiple of the distance between the teeth the pinion will have on its surface space for only a certain number of teeth and a fraction of a tooth. This would mean that the pinion would 75

be made with a certain number of teeth and a wide space somewhat less than the distance between two teeth. In Fig. 9 such wide space is shown at 69.

5 In order that the gear sector 16 and pinion 17 may function properly it is desirable that the rest position of the pinion should be such that one of the teeth thereof will always be in position to be engaged by the end tooth of the rack 16 when the latter comes into position to engage the pinion, and we have, therefore, provided means which normally holds the pinion in this position. The spindle 63 is formed with a flat surface 70 which, when the pinion is at rest, is adapted to engage the flat edge 71 of a spring-pressed positioning lever 72, the latter being pivotally mounted at 73 and being acted on by a spring 74 which urges it yieldingly toward the spindle. This lever 72 thus yieldingly holds the pinion in the position shown in Fig. 9 wherein the tooth next to the wide space 69 is in position to be engaged by the end tooth of the rack sector 16 when the latter comes into operative position. When this occurs the pinion 17 will 20 be given its turning movement and the lever 72 will be forced backwardly against the action of the spring by the camming action of the end of the flat face 70 against said lever. The length of the rack 16 is such that at each rotation of 25 the head 10 said rack will give the pinion approximately one revolution, and when the rack 16 passes out of engagement with the pinion the spring-pressed lever 72 will cooperate with the flat face 70 to bring the pinion to rest in 30 the position shown in Fig. 9.

The mechanism for inking the type member 9 which is herein shown, is specially constructed to handle efficiently quick-drying ink without becoming clogged due to the quick-drying qualities of the ink. This inking mechanism comprises an ink reservoir 75 having an ink-receiving chamber 76 and an ink-delivery roll 77 operating in said chamber and with which the type on the type member 9 contact during the rotative movement of the head 10 whereby said type characters become properly inked for making the printed impression. The ink reservoir 75 is open at one side as shown at 78 and the roll 77 projects sufficiently through said open side so that it will be engaged by the type 9 during the rotation of the head 10. The ink reservoir 75 is provided with a blade 79 which engages the surface of the ink-distributing roll 77, as shown in Fig. 8. The ink roll is rotated in the direction of the arrow Fig. 8 and during such rotation a film of ink will be carried on the surface of the roll past the blade 79. This blade is adjustably secured to the ink reservoir so that the thickness of the film of ink can be regulated. For this purpose the blade is clamped to the reservoir by means of a clamping plate 80 and clamping screws 81, and said blade is provided with slots 82 through which the screws pass and which permit it to have the necessary adjustment.

The ink reservoir 75 is provided with a block or dam 83 which is adjustable in a radial direction and which closes one end of the ink-receiving chamber 76 and also serves to hold the ink-distributing roll in contact with the edge of the blade 79. This block or dam 83 can be adjusted by means of an adjusting screw 84 which is screw-threaded through the wall of the ink reservoir 75 and which is provided with

a lock nut 85 by which it may be locked in position.

The ink reservoir 75 is located a short distance from the turret 4 and in such position that during each rotation of the head 10 the type member 9 will be brought into engagement with the inking roll 77 just before said type member comes into position to engage the article to be marked so that a minimum time interval elapses between the inking of the type 10 9 and the printing operation.

Means are also provided for positively rotating the ink roll 77 while the type is contacting therewith and at the same surface speed as that of the type member so that there will be a rolling contact between the ink roll 77 and the type member 9 during the inking rotation. The means for rotating the ink roll operates to rotate said roll intermittently, that is, it gives the ink roll its rotating movement while the type member 9 is in contact therewith for receiving ink, but becomes inoperative as soon as the type member has moved out of contact therewith. Hence, the ink roll is positively rotated while it is supplying ink to the type on the type member 9, but remains at rest from the time the type member passes out of engagement therewith, and while the type member is completing its revolution and is about to engage the ink roll again.

The means for thus intermittently rotating the ink roll is constructed so that the rotative movement of the ink roll begins just before the type member 9 comes into contact therewith so that when the type member does thus contact the roll it will come into contact with the rotating roll which is rotating at the same surface speed as that of the type member.

The ink roll 77 is made fast to a shaft 86 which is mounted for rotation in suitable bearings 87 carried by a supporting member 88. This shaft 86 has loosely mounted thereon a constantly rotating pinion 89 which is geared to and is driven by the shaft 11. Said shaft 11 has a gear 90 fast thereon which meshes with and drives a pinion 91, and the latter has rigid therewith a gear 92 which meshes with another gear 93 that in turn meshes with the pinion 89 as shown best in Fig. 3. As stated above, the pinion 89 is normally loosely mounted on the shaft 86 and is free to rotate thereon. We have, however, provided means for clutching said pinion to the shaft 86 at such time as the ink roll 77 is to be rotated. For this purpose the pinion 89 is shown as having one or more clutch pins 94 which are adapted to engage with cooperating clutch pins 95 carried by a clutch member 96 that is splined to the lower end 97 of the shaft 86, and means are provided for raising the clutch member 96 to bring the clutching pins 95 into engagement with the clutch pin 94 at a point in the rotation of the head 10 just before the type member 9 comes into contact with the ink roll 77, that is, when the type member 9 and the ink roll are approximately in the relative positions shown in Fig. 8, and to retract the clutch member 96 out of clutching engagement as soon as the type member 9 has moved past the ink roll 77. The means we have adopted for accomplishing this comprises a cam member 98 mounted on the shaft 11 and cooperating with a follower 99 carried on the end of a lever 100 which is pivoted intermediate of its ends to the frame at 101. The outer end of this lever 100 has secured thereto a yoke 102 which

embraces the clutch sleeve 96 and which is provided with two oppositely disposed pins 103 that operate in a peripheral groove 104 with which the sleeve 96 is provided. The clutch-actuating lever 100 is acted on by a pulling spring 105 which is connected at one end to said lever and at the other end is anchored to the frame as shown at 106. This spring tends to raise the outer end of the lever 100 and maintains the follower 99 in contact with the cam 98. This cam 98 is provided with a relatively short low portion 107 and with the high portion 108. So long as the roll 99 is resting on the high portion the outer end of the lever 100 will be in its lowered position and the clutch member 96 will be disengaged from the pinion 89. When the low portion 107 of the cam comes into register with the roll 99 then the spring 105 swings the outer end of the lever upwardly sufficiently to move the clutch sleeve 20 96 into clutching engagement with the pinion 89, and when this occurs the shaft 86 and the ink roll 77 will be positively rotated. As soon as the low portion 107 of the cam passes out from under the roll 99 and the latter again moves 25 onto the high portion 98, then the clutch will be disengaged and the inking roll will come to rest. Since the ink roll is positively rotated during the type-inking operation and since the rotative movement of the inking roll is initiated 30 just before the type member comes into contact therewith, said type member will always have contact with the freshly inked surface of the roll, and this is important where a quick-drying ink is being used because the type member will 35 never be brought into contact with a portion of the ink roll on which the ink has been allowed to dry.

The ink reservoir is adjustably mounted so that it can be placed at different elevations to correspond to any vertical adjustment of the type member 9 and so that it can have different positions in a radial direction to correspond to any radial adjustment of the type member 9.

The ink reservoir 75 is provided with top and bottom plates 110 and 111 which engage the top and bottom ends of the ink roll 77, the latter having a hub portion 112 which projects through the upper plate 110, and is provided with a set screw 109 by which the ink roll is secured to the shaft 86. The ink reservoir is thus supported on the ink roll. Said ink reservoir is provided with a laterally extending arm 113 having an opening in its end through which extends a positioning pin 114 that rises from the supporting member 88. Said reservoir is also provided with a second laterally extending arm 115 to which is connected a pulling spring 116, said spring tending to swing the reservoir toward the head 10. The vertical adjustment of the ink reservoir is obtained by loosening the set screw 109 and adjusting the ink roll 77 vertically on the shaft 86. During this adjustment the arm 113 will slide up or down on the positioning pin 114. Since the ink reservoir is carried by the roll the adjustment of the roll will result in a vertical adjustment of the ink reservoir. The radial adjustment of the ink roll 77 to correspond to any radial adjustment of the type member 9 is accomplished by adjusting the supporting member 88 in which the shaft 86 is rotatably mounted. This supporting member 88 is adjustably mounted on an arcuate-shaped bracket 117 which is secured to the frame 7. One end 119 of the supporting member 88 is secured to the bracket 117 by means of a screw

118 and the other end 120 of said supporting member is secured to said bracket through the medium of another clamping screw 121. The end 120 of the supporting member 88 is formed with a slot 122 through which the screw 121 extends and when this screw is loosened said supporting member 88 can be swung slightly about the screw 118 as a pivot thereby moving the shaft 86 toward or from the head 10. To provide for adjusting the supporting member 88 we have herein illustrated two adjusting screws 123, 124. The screw 123 extends through and has screw-threaded engagement with an ear 125 on the bracket 117 and the end of said screw 123 engages the side of the end 120 of the member 88. The other screw 124 extends loosely through the ear 125 and the end thereof has screw-threaded engagement with said member 88. By backing off the screw 124 and turning up the screw 123 the left-hand end of the supporting member 88 will be moved downwardly in Fig. 6 about the screw 118 as a pivot thereby moving the shaft 86 toward the head 10. On the other hand, if the screw 123 is backed off and the screw 124 is turned up the left-hand end of the supporting member 88 in Fig. 6 will be moved upwardly thereby moving the shaft 86 away from the head 10. In this way it is possible to so adjust the inking roll that it will always have the proper position to provide the necessary rolling contact between said roll and the type member 9 during the type-inking operation.

We claim:

1. A marking machine having in combination a type member, an inking device therefor comprising an ink reservoir and an ink supply roll, means to move the type member in a circular path tangential to said roll, a shaft on which said roll is mounted, a constantly rotating shaft-rotating member, and means to clutch said member to the shaft just before the type member contacts with the roll and to unclutch said constantly rotating member from the shaft when the type member moves out of contact with said roll.

2. A marking machine having in combination a type member, an inking device therefor comprising a shaft, an ink roll fast on the shaft, an ink reservoir mounted on and carried by said ink roll, means to move the type member in a path tangential to said roll, and means to rotate the shaft and thus rotate the roll while the type member is in contact therewith.

3. A marking machine having in combination a type member, an inking device therefor comprising a shaft, an ink roll fast on the shaft but adjustable longitudinally thereof, an ink reservoir mounted on and carried by said ink roll, means to move the type member in a path tangential to said roll and means to rotate the shaft and thus rotate the roll while the type member is in contact therewith.

4. A marking machine having in combination a type member, an inking device therefor comprising a vertical shaft, an ink roll fast on the shaft, an ink reservoir mounted on and carried by said ink roll, said reservoir having an opening in one side through which the roll projects, means to move the type member in a path tangential to said roll and means to rotate the shaft and thus rotate the roll while the type member is in contact therewith.

5. A marking machine having a rotary turret, an article holder for holding a cylindrical article rotatably mounted thereon and provided with

gear teeth, a type member, means to rotate the latter in a path tangential to the article held in the article holder, a gear segment rotatable with the type member and adapted to engage the gear teeth of the article holder thereby to rotate the latter while the type member is in printing contact with the article held in the article holder, yielding means normally holding the article holder at rest in a predetermined angular position, 10 said means permitting rotation of the article holder by the engagement of the gear teeth thereof with the gear segment and being operative to yieldingly restrain rotative movement of the article holder only when the latter is in said 15 predetermined angular position.

6. A marking machine having a supporting member, an article holder for supporting a cylindrical article rotatably mounted thereon and provided with gear teeth, a type member, means to 20 rotate the latter in a path tangential to the article held in the article holder, a gear segment rotatable with the type member and adapted to engage the gear teeth of the article holder thereby to rotate the latter while the type member is in 25 printing contact with the article held in the article holder, said article holder having a flat surface and a spring pressed lever cooperating with said flat surface and normally holding the article holder in a predetermined angular 30 position, while permitting said article holder to rotate when the gear segment engages said gear teeth, said spring pressed lever bringing the article holder to rest in said predetermined angular position when the gear segment passes 35 out of engagement with said gear teeth.

7. A marking machine comprising a rotatable turret member, a plurality of article holders each adapted to hold a cylindrical article rotatably mounted on the turret member, each article holder being provided with gear teeth, means to 40 rotate the turret member with a step-by-step movement to bring the articles carried thereby successively into printing position, a type member, means to rotate the latter in a path tangential to the article which is in printing position, a gear 45 segment rotatable with the type member and adapted to engage the gear teeth of the article holder which is in printing position, thereby to rotate the latter while the type member is in printing contact with the article held thereby, each article holder having a flat face, a spring 50 pressed lever for each article holder normally engaging said flat face and holding the article holder in a predetermined angular position, each lever permitting the corresponding article holder to rotate when the gear teeth thereof are engaged by the gear segment and bringing the article holder to rest in said predetermined angular position when the gear segment passes out of contact 55 with said gear teeth.

8. A marking machine having in combination a type member, an inking device therefor comprising a normally idle shaft, an ink roll fast on the shaft, an ink reservoir in which said ink roll operates, means to move the type member in a circular path tangential to said roll, a constantly 60 rotating shaft-rotating member, and means to clutch said shaft-rotating member to the shaft just before the type member contacts with the ink roll and to unclutch said constantly rotating member from the shaft when the type member moves out of contact with said ink roll.

9. A marking machine having in combination

a type member, an inking device therefor comprising a normally idle shaft, an ink roll fast on the shaft, an ink reservoir mounted on and carried by the ink roll, means to move the type member in a path tangential to said roll, a constantly 5 rotating shaft-rotating member, and means to clutch said shaft-rotating member to the shaft just before the type member contacts with the ink roll and to unclutch said member from the shaft when the type member moves out of contact with said ink roll.

10. A marking machine having in combination a type member, an inking device therefor comprising a normally idle vertical shaft, an ink roll fast on the shaft, an ink reservoir mounted on 15 and carried by said ink roll, said reservoir having an opening in one side through which the roll projects, means to move the type member in a path tangential to said roll, a constantly rotating shaft-rotating member, and means to clutch said 20 member to the shaft just before the type member contacts with the ink roll and to unclutch said member from the shaft when the type member moves out of contact with the ink roll.

11. A marking machine having in combination a turret member rotatable about a horizontal axis, a plurality of rotary article holders carried by the turret member and each rotatable about an axis extending radially to that of the turret member, means to rotate the turret member intermittently to bring each of the articles carried by the article holders in turn into printing position, in which position the axis of the article holder stands vertically, a vertical shaft, a type member carried thereby, means to rotate the 30 shaft, said type member during its rotative movement having a rolling contact with the article which is in printing position, a steady rest adapted to engage the article which is in printing position, a spring for holding the steady rest yielding in engagement with said article, a cam carried by said vertical shaft, and means actuated by the cam to retract the steady rest against the action of the spring when the turret is stepped forward.

12. A marking machine having a turret rotatable about a horizontal axis, a plurality of rotary article holders carried thereby, each article holder adapted to hold a cylindrical article at one end and being rotatable about an axis extending radially to that of the turret, means to rotate the turret with a step-by-step movement to bring the article holders successively into printing position with their axes extending vertically, a type member, means to move the type member in a 40 circular path about a vertical axis and tangential to the article held by that article holder which is in printing position, thereby to make a printed impression on said article, means to rotate the article holder while such printed impression is being made, a vertically movable steady-rest, a spring acting on the steady-rest and tending to move it into operative engagement with the article which is in printing position, and a cam device operative to raise the steady-rest 50 against the action of the spring after each printing operation and to release said steady rest just before each printing operation, whereby the spring, when released, moves the steady-rest into its operative article-engaging position.
